UNITED STATES PATENT OFFICE.

RICHARD HENRY TASKER, OF LIVERPOOL, ENGLAND.

KNIFE FOR USE IN FLAYING CATTLE AND LIKE PURPOSES.

Application filed February 11, 1926, Serial No. 87,609, and in Great Britain January 14, 1926.

This invention relates to improvements in knives for use in flaying cattle and the like purposes.

The usual type of slaughterer's skinning knife used for this purpose comprises a blade with a convex curved cutting edge and an approximately concave back. Great skill is required in using such knives to prevent racking and consequent damage to the hide.

One of the objects of the present invention is to prevent damage to the hides by spacing the tip of the knife away from the hide.

According to the present invention I provide a knife having a projection secured to the side of the blade to space the blade away from the hide. The projection is preferably detachably secured. Since it is the tip of the knife which damages the hide it is desirable to provide the projection on the blade in the neighbourhood of the tip so as to leave the tip free to use but spaced away from the hide to prevent damage. The projection is suitably of smooth contour preferably in the form of a domed stud. It is preferable also that the projection to be detachable so that it can be removed when the knife requires to be sharpened.

The detachable smooth projection is preferably secured in a hole in the blade of the knife near the tip e. g. by means of a screw. Two or more holes may be provided in the blade of the knife at different distances from the edge so that when the blade has worn with use, the stud may be moved into a more suitable hole.

The invention includes a knife having one or more holes in the blade in the neighbourhood of the tip for securing a detachable projection to the tip. The invention also includes a domed stud drilled and tapped to be secured on to the blade of a knife by a screw. The stud may be drilled eccentrically so as to allow it to be moved away from or towards the edge of the blade by rotation if desired.

The accompanying drawings illustrate a preferred form of my invention in which:—

Figure 1 shows a plan view of a flaying knife adapted to hold a stud.

Figure 2 shows an elevation of the knife in Figure 1 with the stud in position.

Figure 3 shows a plan view of the knife shown in Figure 2.

Figure 4 shows a plan view of a blade with a modified form of stud.

The blade 1 of the knife has a handle 2. The cutting edge 3 of the blade curves back towards the tip 4 and the blade is provided with holes 5 and 6. When the knife is new a domed stud 7 is secured in the hole 5 by the countersunk screw 8. When it is necessary to sharpen the knife the stud 7 can be removed. When the knife has worn so that the hole 5 is too close to the edge the stud may be placed in the hole 6. The operator can however, improve the edge by the aid of a steel without removal of the stud 7.

In Figure 4 the stud 7 is held by a screw 70 passing through it eccentrically. When the knife is new the stud is placed so that it is close to the blade as possible. As the knife wears it may be placed in fresh positions in the same hole, further from the edge of the blade. A fresh dome smaller than the first may be used in the hole 6.

The invention is not limited to the preferred construction shown above. For left handed workers the stud may be placed on the other side of the blade. Or studs may be placed on both sides although I prefer to keep one side unobstructed.

The stud may take the form of a round headed screw with a shank but I prefer to have a drilled stud and a screw secured from the other side of the blade. The head of the securing screw 8 on the drawings may be recessed for a screw-driver or suitably formed to be fastened with the fingers.

The knife illustrated is a form commonly employed but the invention is equally applicable to a straight knife or any other form. More than two holes may be provided if required.

The projection is not necessarily dome shaped although I prefer to provide one with a smooth contour, since this causes less obstruction. The projection may be integral with the knife although it is desirable that it be removable.

I declare that what I claim is:—

1. A flaying knife having a smooth stud mounted on the convex side of the blade near the tip.

2. A flaying knife having a detachable smooth stud mounted on the convex side of the blade near the tip.

3. A flaying knife having a domed stud mounted on the side of the blade, near the tip.

4. A flaying knife having a smooth stud

secured to the convex side of the blade near the tip by a screw passing through said blade and engaging said stud.

5. A flaying knife having a smooth stud secured to the side of the blade near the tip by a screw passing through said blade and engaging said stud eccentrically.

6. A flaying knife having a plurality of closely adjacent holes in the blade near the tip for securing a smooth projection to the side of the blade.

10. A flaying knife having a perforation in the blade near the tip and a domed stud

secured on to said blade by a screw passing through said perforation and engaging a 15 threaded socket in said domed stud.

8. A flaying knife having two perforations in the blade near the tip and a domed stud secured on to said blade by a screw passing through one of said perforations and countersunk therein and engaging said domed stud. 20

In witness whereof I have hereunto signed my name this 2nd day of February, 1926.

RICHARD HENRY TASKER.
